(57) CLAIM

We claim the ornamental design for a garment, as shown and described.

DESCRIPTION

FIG. 1 is a front perspective view of a garment.

FIG. 2 is a rear perspective view of the garment shown in FIG. 1.

FIG. 3 is a front view of the garment shown in FIG. 1.

FIG. 4 is a rear view of the garment shown in FIG. 1.

FIG. 5 is a right side view of the garment shown in FIG. 1; and,
